UNITED STATES PATENT OFFICE.

HIRAM R. GRAY, OF CHICAGO, ILLINOIS.

JAR-HOLDER.

1,331,758.

Specification of Letters Patent. Patented Feb. 24, 1920.

Application filed September 25, 1919. Serial No. 326,248.

To all whom it may concern:

Be it known that I, HIRAM R. GRAY, a citizen of the United States, residing at Chicago, in the county of Cook and State of Illinois, have invented certain new and useful Improvements in Jar-Holders; and I do declare the following to be a full, clear, and exact description of the invention, such as will enable others skilled in the art to 10 which it appertains to make and use the same.

This invention relates to improvements in jar holders.

The primary object is to provide a jar holder including a novel means for holding the jaws and handles in such a position that extremely quick operation is rendered possible.

With the above and other objects in view, 20 the invention consists of certain novel features of construction and the combination and arrangement of parts as will be more fully set forth in the specification and claim.

I attain these objects by constructing the 25 device as clearly illustrated in the accompanying drawings, in which—

Figure 1 is a perspective view of the jar holder and cap-remover in operation; and

Fig. 2 is a vertical longitudinal sectional 30 view of the jar holder.

The jar holder broadly comprises a base formed of any suitable material and of any preferred shape, a post rising from the base and preferably but not necessarily formed 35 integral therewith, a pair of jar engaging jaws having operating handles and being pivotally mounted on said post and means for retaining the jaws and handles in position for quick operation.

40 In detail as illustrated, I employ a base 1 which may be formed of wood or metal, said base being substantially elliptical in conformation and provided adjacent one end with a post 2 which is formed integral 45 with the base as shown. The post is provided with a vertical bolt hole which aligns with a bolt hole of the same diameter in the base.

A pair of jar engaging jaws 3 are provided, said jaws having at one end a pair 50 of overlapping apertured ears 4 through which is passed a bolt 5, said bolt being of such a length that it will pass through the bolt holes in the post and base, the bolt being adapted to receive a nut on its lower 55 end, said nut being countersunk in the recess formed around the bolt hole in the base.

A pair of handles 6 is formed on the other end of the jaws and are movable toward and away from each other to contract the jaws 60 around the jar or to release the jar.

In order that the handles and jaws may be at all times in position for quick operation, a support 7 in the form of a block or the like is provided, said block being provided with a notch 8 in its upper edge for the reception of the handles 6, said notch being of such a width as to hold the handles close enough together to permit a person to easily grasp them in one hand. 70

From the foregoing description, taken in connection with the accompanying drawings, the construction and operation of the invention will be readily understood without requiring a more extended explanation. 75

Various changes in the form, proportion and the minor details of construction may be resorted to without departing from the principle or sacrificing any of the advantages of the claimed invention. 80

I claim:—

A fruit jar holder comprising a base, a post rising vertically from said base, a pair of jar engaging jaws pivotally connected at one end to said post, a pair of outwardly 85 diverging substantially horizontal handles formed on said jaws, a second post rising from said base, a pair of stops carried by said second post and adapted to engage the outer faces of said handles to restrict the 90 outward movement thereof and hold them in position for quick operation.

In testimony whereof I have hereunto set my hand.

HIRAM R. GRAY.
